C. GAVED

MECHANISM FOR FEEDING SHEETS OF MATERIAL TO PRINTING AND OTHER MACHINES

Filed May 2, 1922

UNITED STATES PATENT OFFICE.

CLEMENT GAVED, OF ANERLEY, LONDON, ENGLAND, ASSIGNOR, BY MESNE ASSIGNMENTS, TO H. T. B. LIMITED, OF WALTHAMSTOW, LONDON, ENGLAND.

MECHANISM FOR FEEDING SHEETS OF MATERIAL TO PRINTING AND OTHER MACHINES.

Application filed May 2, 1922. Serial No. 557,992.

To all whom it may concern:

Be it known that I, CLEMENT GAVED, a subject of the King of England, residing in Anerley, London, England, have invented 5 certain new and useful Improvements in Mechanism for Feeding Sheets of Material to Printing and Other Machines, of which the following is a specification.

This invention consists in improvements 10 in or relating to mechanism for feeding sheets of material into printing or other machines and refers particularly to improvements in those devices, sometimes known, and hereinafter referred to as "strokers". 15 The type of stroker-device to which the present invention relates is that in which an arm, secured at one end to a rotatable shaft, carries at its free end a pad which, as the shaft is rotated, is brought into contact with 20 the top sheet of a pile of sheets and is pressed thereon so that rotational movement of the stroker-arm draws the top sheet forwardly to, for example, the lay-board of a printing machine. Hitherto the stroker- 25 arms have been themselves resilient, for example, they have been formed of spring steel or the like and have extended in a radial direction from the rotatable shaft aforesaid.

It is found that these arms, after a time, 30 become deformed and their resilience impaired, which necessitates frequent renewal of them. This is objectionable and it is the object of the present invention to provide a stroker in which such objection will not 35 exist.

According to the present invention a stroker comprises the combination with a crank-arm or equivalent device secured to a rotatable shaft, generally rotatable about a 40 fixed axis, of a substantially rigid stroker-arm pivotally carried in the said crank-arm with the axis of pivoting parallel to, but spaced from, the axis of said shaft and resilient means to control the movement of 45 the stroker-arm about its axis of pivoting. The purpose of the resilient control is to tend to resist movement of the arm about its axis of pivoting as the pad is brought into contact with, and pressed on to, the 50 top of the pile of paper-sheets and to return the said arm, after it is disengaged from the pile of sheets, to its initial position from which it had been displaced by engagement of the pad with the pile.

Preferably there is a resilient buffer interposed between the stroker-arm and a rigid stop which is fixed in its relation to the shaft aforesaid, the buffer serving as a shock-absorber as the stroker is returned, under the action of its resilient controlling-means, 55 against the fixed stop.

Conveniently the stop is adjustable in such a manner as to regulate at will the normal position of the stroker-arm before it is moved about its pivot by engagement with 60 the pile of sheets.

One preferred embodiment of the invention will now be described in detail by way of example with reference to the accompanying drawings in which— 70

Figure 1 is a side elevation of the stroking device, and

Figure 2 is an end elevation of the device.

Like reference numerals denote similar 75 parts in both figures of the drawings.

On the customary stroker-shaft 5 or its equivalent is secured a short radial crank or arm 6 hereinafter referred to as the "crank-arm". The crank-arm is formed integral with a detachable two-part boss 7 which can be bolted to the shaft by means of extensions 8 which project radially from the shaft at right-angles to the crank-arm. 80

A substantially rigid metal stroker-arm 9 of T-section, is pivotally mounted at 22, intermediate of its length, in the outer extremity of the crank-arm. At one end the stroker-arm has secured to it by bolts 10 and washers 11, a pad 12 of leather, rubber 90 or other comparatively soft material. At its opposite end the stroker-arm is connected to one extremity of a tension-spring 13, the other extremity of which spring is connected with a hooked rod 14 movable endwise in a 95 guide 15 formed on a prolongation of the lower of the extended portions 8 by which the boss 7 is bolted to the stroker-shaft. The hooked rod is screw-threaded and is engaged with an adjusting-nut 16 which abuts 100 an end face of the guide 15, there being a small wedge-shaped projection 17 on the nut which will fit into corresponding recesses in the guide to hold the nut in any position of adjustment to which it has been moved in 105 adjusting the tension of the spring.

Extending outwardly from the boss 7, at a position between the arm 6 and the spring

13, is a screw-bolt 18 serving as an adjustable stop for the stroker-arm, the position of the stop being adjustable by screwing it more or less into a screw-threaded recess 19 formed for its reception in the boss. A lock-nut 20 is provided to maintain the stop in any position of adjustment and on the end of the stroker-arm remote from the pad, is a rubber sleeve 21, which acts as a buffer or shock-absorber to engage with the head of the stop.

It will be understood, therefore, that as the stroker-shaft is rotated in the direction of the arrow in Figure 1, the stroker-pad 12 becomes first engaged with the top sheet of a pile of sheets (not shown) and is thereafter rocked about its pivot 22 by the continued rotation of the shaft 5, tensioning its control-spring 13 in so doing.

20 It will be understood that the pile of sheets would be located below and somewhat to the right of the position of the stroker pad as shown in Figure 1 of the drawings, and that the top sheet would be carried forward by the stroker-arm on to a support such as the lay-board of a printing machine. As the stroker-arm moves towards a horizontal position on the right of the stroker shaft, the pad leaves the pile of sheets and the control-spring re-asserts itself and returns the stroker-arm to its initial or normal position until the buffer 21 is engaged with the head of the fixed stop 18 thus absorbing any shock of the blow of the stroker-arm on the stop.

25 The latter limits the return of the stroker-arm and also serves to adjust the initial or normal position thereof.

With the construction hereinabove described, a substantially rigid and strong stroker-arm is provided having the advantageous features of the resilient stroker-arm hereinbefore employed but devoid of the disadvantages referred to above which accrued from the use of a stroker-arm formed 40 of spring strip.

What I claim as my invention and desire to secure by Letters Patent is:—

1. A stroker of the type described comprising in combination a boss adapted to be secured on a shaft which is rotatable in one direction about a fixed axis, a radial crank secured to said boss, a rigid stroker arm pivotally mounted intermediate its ends on the outer end of said crank, a radial projection from said boss substantially at right angles to the crank aforesaid, a spring in tension between said radial projection and the end of the stroker arm adjacent thereto, a rigid stop located in the path of that end of the stroker arm to which the spring is attached, and a resilient buffer interposed between the stroker arm and the rigid stop aforesaid, substantially as described.

2. A stroker of the type described comprising in combination a boss adapted to be

secured on a shaft which is rotatable in one direction about a fixed axis, a radial crank secured to said boss, a rigid stroker arm pivotally mounted intermediate its ends on the outer end of said crank, a radial projection from said boss substantially at right angles to the crank aforesaid, a spring in tension between said radial projection and the end of the stroker arm adjacent thereto, a rigid stop located in the path of that end of the stroker arm to which the spring is attached, and means whereby said rigid stop is adjustable in such a manner as to regulate the normal position of the stroker arm when it is at rest against said stop and before it is moved about its pivot by engagement with a pile of sheets, substantially as described.

3. A stroker of the type described comprising in combination a boss adapted to be secured on a shaft which is rotatable in one direction about a fixed axis, a radial crank secured to said boss, a rigid stroker arm pivotally mounted intermediate its ends on the outer end of said crank, a radial projection from said boss substantially at right angles to the crank aforesaid, a spring in tension between said radial projection and the end of the stroker arm adjacent thereto, a rigid stop located in the path of that end of the stroker arm to which the spring is attached, 85 a resilient buffer interposed between the stroker arm and the rigid stop aforesaid, and means whereby said rigid stop is adjustable in such a manner as to regulate the normal position of the stroker arm when it is at rest against said stop and before it is moved about its pivot by engagement with a pile of sheets, substantially as described.

4. A stroker of the type described comprising in combination a shaft adapted for continuous rotation in one direction only, a boss having means to secure it to said shaft, a radial crank integral with said boss, a rigid stroker arm pivotally mounted intermediate its ends on the outer end of said crank, a radial projection extending from said boss substantially at right angles to the crank aforesaid, a spring-tension-adjusting device slidably mounted in said radial projection so as to move endwise towards and away from the stroker arm, means to adjust the position of said spring-tension-adjusting device, a spring in tension between said latter device and the end of the stroker arm adjacent thereto, a rigid stop operatively connected to said boss and extending therefrom so that its outer end is located in the path of that end of the stroker arm to which the spring is attached, means to adjust the position of said rigid stop in relation to the stroker arm, and a resilient buffer interposed between the stroker arm and the adjacent end of the rigid stop, substantially as described.

5. A stroker for the purpose described

comprising in combination a rotatable shaft, a crank-arm secured thereto by means of a two-part boss, a substantially rigid stroker-arm pivoted to the outer end of said crank-arm at a position intermediate in the length of the stroker-arm with the axis of pivoting parallel to the axis of the shaft, a pad at one end of the stroker-arm, a tensioning-spring one end of which is secured to the other end of the stroker-arm, a projection from the boss aforesaid extending parallel to and in the same direction as that end of the stroker-arm to which the spring is secured, spring-tensioning means in said projection which tensioning-means is engaged with the other end of the tensioning-spring aforesaid, and an adjustable stop engaged between the said boss and the stroker-arm intermediate in that end of the latter between its pivot and its connection with the tensioning-spring. 25

6. A stroker for the purpose described comprising in combination a rotatable shaft, a crank-arm secured thereto by means of a two-part boss, a substantially rigid stroker-arm pivoted to the outer end of said crank-arm at a position intermediate in the length of the stroker-arm with the axis of pivoting parallel to the axis of the shaft, a pad at one end of the stroker-arm, a tensioning-spring one end of which is secured to the other end of the stroker-arm, a projection from the boss aforesaid extending parallel to and in the same direction as that end of the stroker-arm to which the spring is secured, spring-tensioning means in said projection which tensioning-means is engaged with the other end of the tensioning-spring aforesaid, and an adjustable stop engaged between the said boss and the stroker-arm intermediate in that end of the latter between its pivot and its connection with the tensioning-spring. 30
